CAR END CONSTRUCTION

Filed June 4, 1920

3 Sheets-Sheet 3

UNITED STATES PATENT OFFICE.

WALTER P. MURPHY, OF NEW YORK, N. Y.

CAR-END CONSTRUCTION.

Application filed June 4, 1920. Serial No. 386,477.

My invention relates to reinforced metal end wall structures for railway cars, and more particularly to freight box cars.

The primary object of my invention is the provision of a sheet metal end wall, formed of one or of more than one section, which is reinforced to withstand more adequately than heretofore not only the stresses and strains set up by the thrust against the same of a shifting cargo, but also especially the stresses and strains set up by the swaying and weaving of the car in transit, or other distortions resulting from the stopping or starting of the train or the shocks in switching. It is particularly difficult to reinforce a box car against swaying and weaving, and the stresses set up thereby. Such swaying and weaving is caused not only by the contents of the car, but also in large measure by the car itself, due to the weight of the superstructure and particularly to its height. Weaving stresses are usually bending stresses caused by the bending of the walls and roof of the car about the floor structure.

My invention consists in forming the sheet or sheets composing the end wall with vertical and diagonal corrugations, so disposed as to very effectively resist the rupture, bending, or distortion of the end wall by any stresses to which this portion of the car is subjected when in service.

The invention consists further in the novel and improved arrangements and constructions for accomplishing the above stated objects, and such other incidental objects as will appear from the following description of my invention as illustrated in the accompanying drawings.

The invention is illustrated in certain preferred embodiments in the accompanying drawings, wherein:

Fig. 1 is a view in elevation of the end wall of a car, showing the preferred form of construction;

Fig. 2 is a sectional view taken along the line 2—2 of Fig. 1 the same being shown on a larger scale;

Fig. 3 is a similar sectional view taken along the line 3—3 of Fig. 1;

Fig. 4 is a vertical section taken along the line 4—4 of Fig. 1;

Fig. 5 is an elevation of another modification;

Fig. 6 is an elevation of still another modification; and

Fig. 7 is a side elevation partly in section along the line 7—7 of Fig. 6.

Like characters of reference designate like parts in the several figures of the drawings.

In the construction of my improved car end as shown in Fig. 1, 10 designates a plate of sheet metal formed in two sections 11 and 12, overlapping and suitably riveted together along the central line 13 of the car and of such size and contour as to form the entire end wall of the car body. The sections 11 and 12 are preferably formed with vertical marginal flanges 14 by means of which the end sheet may be secured to the side framing of the car. As shown in Fig. 4 the upper edge of the end sheet is preferably formed with an inwardly extending flange 15 for securing the upper edge of the sheet to the superstructure of the car. The lower edge of the sheet is preferably secured to the underframe by means of two angle irons 16 and 17 between which the sheet is riveted or otherwise suitably fastened.

I have shown at 18 a conventional form of roof structure. The particular design of roof structure used with my invention is obviously immaterial. In Fig. 4, I have shown the flange 15 bent downwardly to form an attaching flange 19 adapted to be secured to the side of the car. A diagonal brace 20 is shown running from the upper end of the car downwardly to assist in bracing the car superstructure. The car may be provided with a wooden lining 21 extending either partially or entirely up the side of the car. At 22, I have shown a wooden lining for the end sheet. This construction is optional. At 23 is a wooden floor and at 24 one of the center sills.

Each of the sections 11 and 12 is formed with a vertical corrugation 11^a and 12^a respectively extending substantially to the upper and lower edges of the sheet and tapering at the ends so as to merge into the sheet. These corrugations are placed adjacent the riveted edges of the sheet and form in effect an end post for taking up the usual stresses imposed on an end post, such as cargo

thrusts. In order to further stiffen the sheet both against distortion from cargo thrusts and distortion because of weaving and swaying stresses I form a series of diagonal and substantially parallel corrugations in the sections 11 and 12 which extend substantially from one edge of the sheet to an adjacent edge. These corrugations designated as 25 preferably decrease in size 10 from the center corrugation to the outer corrugation. The central corrugation 26 which extends from an upper corner of the end sheet toward the bottom of the end post is subjected to greater stresses than the other 15 diagonal corrugations and is accordingly made stronger.

The weaving and swaying of a freight car while in transit sets up stresses which tend to bend the end sheet about a diagonal axis, 20 that is about an axis which extends from one upper corner downwardly to the region of the opposite lower corner. Such stresses are caused by the fact that it is difficult and almost impossible to prevent a relative longitudinal movement of the sides of the car body. Accordingly the upper corners of the end sheets tend to move relatively both to each other and to the underframe of the car. This movement tends to bend the sheet 25 about the diagonal axes referred to. In order to resist this distortion of the sheet, I extend the corrugations 25 diagonally across the sheet so as to effectively resist any bending thereof by weaving or swaying stresses. 30 The corrugations are arranged substantially parallel to one another so as to transmit the stresses imposed by the superstructure and contents of the car on the end sheet practically uniformly along the end of the underframe. This avoids a concentration of 35 the stress at the lower central portion of the sheet. This portion of the sheet as is well known is usually required to sustain the greater portion of the stress caused by cargo 40 thrusts. By means of the uniform distribution of the corrugations over the entire surface of the end sheet the same is reinforced throughout, not only against distortions from swaying and weaving stresses, but 45 against distortions from cargo thrusts and the inertia of the car.

In Fig. 5, I have shown a modification of the end sheet shown in Fig. 1. This construction may be used in cases where a 50 stronger end post is necessary. In this construction the sections 35 and 36 of the end sheets 37 are corrugated so as to form three vertical central corrugations extending substantially the entire height of the sheet. 55 In the construction herein shown two of the corrugations 38 and 40 are formed in the section 35 and the corrugation 39 is formed in the section 36. The two sections are overlapped and riveted along the lines 41 and 42 60 on opposite sides of the corrugation 38. The

end sheet is formed with diagonal corrugations as shown in Fig. 1 and for the purpose already set forth in the description of Fig. 1. Accordingly this construction need not be further described.

In Figs. 6 and 7, I show an end sheet 43 preferably formed of two sections 44 and 45 and riveted along their meeting vertical edges on the line 46. As in Fig. 1 the end sheet is formed with two vertical corrugations 47 and 48 to form an end post. The sections are formed with diagonal corrugations 49, 50, 51 and 52 as shown. These corrugations extend from the extremities of the corrugations 47 and 48 forming the end post 80 and converge toward the outer margin of the sheet. These corrugations together with the central corrugations form in effect trusses which very effectively resist distortions of the sheet by weaving and swaying stresses. 85

The car structure is further rigidified by means of the diagonal brace 53 secured to the marginal flange 54 of the end sheet at the point 55 near the meeting point of the respective pairs of the diagonal corrugations. 90 The brace 53 extends downwardly and is secured at 56 to the underframe of the car.

The end sheets shown in Figs. 5 to 7 inclusive are preferably formed with marginal flanges as shown in Figs. 2, 3, and 4. 95 These end sheets may be formed of a single piece of material but owing to the difficulty of handling a single sheet and also of the waste resulting from distortion of the same when pressing the corrugations therein, it is 100 preferable to form the end sheet from two sections as shown herein.

An end sheet provided as herein shown with reinforcing corrugations running both vertically and diagonally, is not only stiff 105 and strong in itself so as to be capable of withstanding cargo thrusts, but it also effectively resists distortion by weaving and swaying stresses and serves to reinforce and strengthen the framing of the car against 110 weaving strains.

The specific constructions shown in Figs. 7 and 8 are not claimed specifically herein, this modification being described and claimed specifically in my copending divisional application Serial No. 609,010, filed December 26, 1922.

I claim:

1. A sheet metal end structure for railway cars having a central vertical end post formed therein and a series of parallel diagonal corrugations extending from the upper and outer edges of said end structure toward the axis of the end post, said corrugations increasing in size toward the center of the 125 series.

2. A sheet metal end structure for railway cars having a central end post formed therein and a series of parallel corrugations formed therein and decreasing in size from 130

the center of said series and extending from the outer edges of said end structure downwardly and toward the axis of said end post.

5 3. The combination with the underframe and sidewalls of a railway car of a metal end sheet secured to said underframe and sidewalls and corrugated to form a central

end post, said sheet being also formed with substantially parallel corrugations terminating within the edges of the sheet and extending diagonally downward from the edges of said sheet toward the end post so as to resist the distortion of said sheet by weaving stresses.

WALTER P. MURPHY.
